Kenneth A. Patrick, Bethesda, Md., assignor to Bethesda Pastry Shops, Inc., Bethesda, Md., a corporation of Maryland

Application August 21, 1952, Serial No. 21,145

Term of patent 14 years

(Cl. D82—2)

To all whom it may concern:

Be it known that I, Kenneth A. Patrick, a citizen of the United States of America, residing at Bethesda, in the county of Montgomery, State of Maryland, have invented a new, original, and ornamental Design for an Iced Cake, of which the following is a specification, reference being had to the accompanying drawing, forming part thereof.

The figure on the drawing is a front perspective view of an iced cake, showing my new design.

I claim:

The ornamental design for an iced cake, as shown.

KENNETH A. PATRICK.
